UNITED STATES PATENT OFFICE.

BYRON P. WILLETT, OF DETROIT, MICHIGAN.

TOY PISTOL.

1,205,498.

Specification of Letters Patent. Patented Nov. 21, 1916.

Application filed March 27, 1916. Serial No. 86,853.

To all whom it may concern:

Be it known that I, BYRON P. WILLETT, a citizen of the United States of America, residing at Detroit, in the county of Wayne and State of Michigan, have invented certain new and useful Improvements in Toy Pistols, of which the following is a specification, reference being had therein to the accompanying drawings.

10 This invention relates to a toy pistol and the primary object of my invention is to provide simple, durable, inexpensive and easily operated toy pistols having the same sound proclivities as an ordinary pop gun, 15 but devoid of a temporarily sealed air chamber and projectile.

My invention further aims to provide a single or repeating sound producing device in the form of a pistol having a self-cocking trigger by which the sound producing mechanism is actuated, the pistol being harmless and devoid of exposed mechanism or protuberances liable to injure the hands.

20 My invention further aims to provide a pop pistol which from the standpoint of manufacture, can be principally made of scrap material and the parts of the pistol easily and quickly assembled.

25 My invention will be hereinafter described and then claimed, and reference will now be had to the drawing, wherein—

Figure 1 is a view of the inner side of a member adapted to form a half of a toy pistol in accordance with my invention; Fig. 2 is a side elevation of a toy pistol; Fig. 3 is a cross sectional view taken on the line III—III of Fig. 1; Fig. 4 is a view similar to Fig. 1, illustrating a slight modification of my invention, and Fig. 5 is a view 40 of the inner side of a portion of a pistol member, illustrating a further modification of my invention.

The toy pistol is preferably made of sheet metal cut, stamped and pressed to provide 45 two longitudinal members which may be placed in matched registration and suitably connected together, to form a conveniently handled device, such as a pistol having a barrel 1, a breech portion 2, and a handle

or stock portion 3. The members are generally designated A and B and the marginal edges of each member are rounded, as at 4, and said members connected by rivets 5, or other fastening means, at such points where the members may be rigidly and conveniently held together.

The breech portion 2 of the members A and B have embossed or pressed out circular wall portions 6, and the wall portion of the member B has a concentric opening 7.

In the wall portion 6 of the member B is mounted a flexible diaphragm or vibratory sounding plate 8, preferably made of sheet steel with the marginal edges soldered or otherwise connected to the wall portion 6 of the member B. The diaphragm 8 is in spaced relation to the wall portion 6 of the member B, thereby providing a sound chamber 9 from which a single sharp 70 sound may be emitted or similar, successive or ricochet sounds, according to the mechanism employed for flexing, vibrating or striking upon the diaphragm.

The member B has the inner side thereof 75 provided with a flexible or resilient hammer or striker 10 which has one end thereof held by a rivet 11 and in-struck lugs 12, while the opposite end of the hammer extends on to the diaphragm 8 and has a lip 80 or beveled portion 13 approximately central of the diaphragm. The hammer 10 is preferably in the form of a comparatively flat metallic strip which is slightly bent whereby only the outer free end thereof will impinge against the diaphragm, the free end of the hammer having a striking effect against the diaphragm somewhat similar to a blow on a drum head.

Pivots connected to the inner side of 90 the member B, at the breech portion 2 thereof, by a rivet 14 or other pivotal means, is a trigger member 15 having an offset finger grip portion 16 extending through a slot 17 formed by the confronting edges of the members A and B. The trigger member is also made of sheet metal 95 and extends over the diaphragm 8 with the

end thereof bent or shaped to form a cam 18 adapted to ride under the lip 13 of the hammer 10 and elevate said hammer, whereby as the hammer rebounds or assumes normal position it strikes the diaphragm with a blow sufficient to produce a sharp and distinct report. The trigger member 15 is also slightly bent, adjacent the cam 18, whereby it will ride over the end of the hammer 10 when assuming normal position, and to restore said trigger member to normal position, as shown in Fig. 1, a coiled retractile spring 19 has one end thereof connected to an upstruck lug 20 of the trigger member, and the opposite end thereof connected to the member B, at the edge thereof.

With the trigger member 15 made of sheet metal, an edge of the finger grip portion 16 can be bent upon itself, as at 22 to present a rounded edge that will not injure a finger bringing pressure to bear upon the trigger member.

In Fig. 4 of the drawing there is illustrated a slight modification of my invention, wherein a comparatively flat spring 23 is substituted for the coiled retractile spring 21. The spring 23 has one end thereof anchored under in-struck straps 24 of the handle portion 3 of the member 2 and the opposite end of said spring engages under the outstruck lug 20 of the trigger member.

In Fig. 5 there is illustrated a further modification of my invention, wherein a pivoted trigger member 25 has a segment rack 26 meshing with a pinion 27 carried by a bladed wheel 28 suitably connected to the member B to revolve in proximity to the diaphragm of said member. The blades of the wheel have the outer ends thereof provided with cams and bent similar to the end of the trigger member 15, whereby the blades of the wheel will successively actuate the hammer 10 and then recede over said hammer to normal position. The bladed wheel 28 and the trigger member 25 are restored to normal position by a coiled retractile spring 29 connected to the trigger member 25 and to the member B.

In the operation of the preferred form of pistol, it is only necessary to pull upon the finger portion 16 of the trigger member 15 to actuate the hammer 10 and cause a sound to be emitted by the pistol. The trigger member is automatically restored to normal or cocked position and the pistol may be repeatedly fired.

In the modification shown in Fig. 5, a pull upon the trigger member causes successive reports from the pistol, similar to an ordinary automatic pistol. In either instance, a blow struck by the hammer is sufficient to render a sharp report without injur-

ing the diaphragm, and as the hammer actuating mechanism is concealed between the members of the pistol, it is impossible to tamper with the mechanism and the members can be finished to present a neat and attractive appearance.

While in the drawings there are illustrated the preferred embodiments of my invention, it is to be understood that the structural elements are susceptible to such variations and modifications as fall within the scope of the appended claims.

What I claim is:

1. In a toy pistol, a diaphragm carried by a wall of said pistol and in parallelism therewith, a hammer carried by the same wall adapted to impinge upon said diaphragm, and means for operating said hammer.

2. In a toy pistol, a diaphragm carried by a wall of said pistol, a trigger member, and a hammer actuated by said trigger member to impinge upon said diaphragm.

3. In a toy pistol, a diaphragm carried by a wall of said pistol, a normally cocked trigger member, and a hammer normally engaging said diaphragm adapted to be actuated by said trigger member to impinge upon said diaphragm.

4. In a toy pistol, matched longitudinal members, a diaphragm between said members, and a hammer adapted to impinge upon said diaphragm.

5. In a toy pistol, matched longitudinal members, a diaphragm between said members, a normally cocked trigger member, and a hammer adapted to be actuated by said trigger member to impinge upon said diaphragm.

6. In a toy pistol, a breech portion having a sounding chamber, a diaphragm forming a wall of said chamber, means adapted to strike said diaphragm and cause a sound to be emitted from said chamber, and means adapted for operating said diaphragm striking means.

7. In a toy pistol, a breech portion having a sounding chamber, a diaphragm forming a wall of said chamber, a hammer adapted to impinge upon said diaphragm, and means adapted to actuate said hammer and cause sound to be emitted from said chamber.

8. In a toy pistol, a diaphragm, a hammer adapted to impinge upon said diaphragm, means movable in one direction under said hammer to cause said hammer to rebound and produce sound, and movable in the opposite direction over said hammer to assume normal position.

9. In a toy pistol, a diaphragm, a hammer adapted to impinge upon said diaphragm, a trigger member movable in one direction under said hammer to cause said hammer to rebound and produce a sound

from said diaphragm and movable in the opposite direction over said hammer to assume normal position.

10. A toy pistol comprising two longitudinally connected members, a diaphragm carried by one of said members, a resilient hammer normally engaging said diaphragm, and means carried by the same member adapted to raise said hammer whereby said

hammer when released rebounds to strike 10 said diaphragm.

In testimony whereof I affix my signature in presence of two witnesses.

BYRON P. WILLETT.
